DESIGN FOR A COMBINED FIELD DESK AND TRUNK

Frederick T. Paden, Collingswood, N. J.

Application February 7, 1945, Serial No. 117,797

Term of patent 3½ years

(Cl. D33—7)

To all whom it may concern:

Be it known that I, Frederick T. Paden, a citizen of the United States, residing at 3191 Westover Drive, S. E., Washington, D. C., have invented a new, original, and ornamental Design for a Combined Field Desk and Trunk, of which the following is a specification, reference being had to the accompanying drawing, forming a part thereof.

Fig. 1 is a perspective view of the combined field desk and trunk in its operative position as a desk, and

Fig. 2 is a perspective view of the combined field desk and trunk in its closed position.

I claim:

The ornamental design for a combined field desk and trunk, as shown.

FREDERICK T. PADEN.
